UNITED STATES PATENT OFFICE.

ALBERT SPIES, OF LOUISVILLE, KENTUCKY.

RAILWAY-GATE.

No. 894,987.

Specification of Letters Patent.

Patented Aug. 4, 1908.

Application filed April 9, 1907. Serial No. 367,163.

To all whom it may concern:

Be it known that I, ALBERT SPIES, a citizen of the United States of America, residing at Louisville, in the county of Jefferson and 5 State of Kentucky, have invented certain new and useful Improvements in Railway-Gates, of which the following is a specification.

This invention relates to improvements in 10 railway gates and is designed as an improvement on my patent issued on the 6th day of March, 1906, numbered 814,330.

An object of this invention is to so improve the gate in the patent above referred 15 to as to lighten it and reduce the cost of manufacture. By employing this invention the applicant has found that the sections of the gate may be multiplied without making it unwieldy, yet the said gate will possess practically the same strength as it would possess 20 if made entirely of metal.

In order to accomplish the result stated, the inventor has provided joints at the intersections of the parts of the gate and he has 25 provided novel pivotal connections whereby the said sections of the gate are operatively connected.

In order that the mode of use and utility 30 of the invention may be appreciated, reference is made to my former patent, it being understood that the ends of the sections of the gate will be connected with the operating mechanism just as it is in the patent, this invention relating more particularly to the 35 construction of the gate proper.

With the foregoing and other objects in view, the invention consists in the details of construction and in the arrangement and combination of parts to be hereinafter more 40 fully set forth and claimed.

In describing the invention in detail, reference will be had to the accompanying drawings forming a part of this specification wherein like characters denote corresponding 45 parts in the several views, in which—

Figure 1, is a view in elevation of a gate embodying the invention. Fig. 2, is an end view of the gate in its contracted position. Fig. 3, is an edge view of one of the bars. Fig. 4, is an enlarged section view of the 50 couplings for the top of the bars. Fig. 5, is an enlarged sectional view of the coupling for the central portions of the bars. Fig. 6, is a view in elevation of the inner face of one 55 part of a bar A. Fig. 7, is an enlarged inside view of an outer section of the central coup-

ling employed in the invention. Fig. 8, is an enlarged view of a face of the intermediate section of the central coupling. Fig. 9, is an enlarged inside view of an outer section of an 60 end coupling. Fig. 10, is an enlarged view of a face of an intermediate section of the end coupling.

In the drawings A, B, denote the bars of the gate which are duplicated throughout 65 the length of the gate and each bar A, has metallic end caps I, and a center coupling D. The bars A, are in pairs. The bars B, lie between pairs of bars A, and each bar B, has end caps b, and a coupling b'. Each coupling b', is provided with trunnions F, which enter bearings b⁴, in the coupling D, and they may be secured therein in any desired manner, preferably by bolts G, run through the center thereof and secured by a nut g. The 75 couplings D, have apertures d' to receive bolts or rivets for attaching the coupling to the bar. The end caps b are also provided with trunnions H, which have bearings in the end caps I, on the bars A, hence the bars A 80 and B are pivotally connected at their ends and at points intermediate thereof.

The end caps I, are secured to the bars A, by rivets or other securing devices, which are run through apertures i, and each end cap b, 85 is secured to a bar B, by devices run through the aperture b³. The coupling for the bars A and B, at the ends are fully shown in Fig. 2, and in the sectional view, Fig. 4. The coupling for the central portions of the bars A and B, is well shown in Fig. 5. The central portion of the bar B, lies in the coupling b', and has an aperture in its center portion to receive the bearings b⁴. The walls of the couplings b', are provided with apertures b², to 95 receive fasteners for retaining the bar and coupling in assembled relation. As shown in the drawing, the bar A, is a continuous strip having end caps as heretofore described. The bar A, is shown in Fig. 6, as extending 100 through the center coupling.

Should the wooden bars of this gate become broken or otherwise impaired, the said bars may be readily divested of metal fittings and the said fittings may be utilized in connection with perfect wooden bars, so that the cost of repairing is minimized. The metal parts of the gate are of such strength and durability as to withstand wear and hardship.

The coupling for the central portions of the sections A and B is well shown in Fig. 5, and

it will be observed that the inner ends of the portion b^2 , are seated in the aperture of the couplings b , where they are secured in any manner. The intermediate section b^2 , may be a continuous strip having end caps or it may be formed of two strips having their ends seated in the couplings b . The outer sections A, extend from the end caps to the intermediate coupling, but do not extend through the said coupling. This is well shown in Fig. 5.

What I claim is:

1. A coupling for an expansible gate comprising a central hollow body, trunnions projecting from said body, side bodies, and bearings carried by the side bodies to engage the trunnions of the central body.
2. A coupling for an expansible gate comprising a central hollow body closed at one end, trunnions projecting from said body, side bodies, and bearings carried by the side bodies to engage the trunnions of the central body.
3. In an expansible gate, the combination of a central bar, a coupling embracing said central bar intermediate its length, said coupling being provided with trunnions, parallel side bars arranged one on either side of the

central bar, a coupling carried by each of the side bars, bearings carried by the couplings of the side bars to engage the trunnions of the coupling of the central bar, and means for pivotally uniting the ends of the central bar and the side bars, said side bars being suitably perforated to permit the engagement of the trunnions and the bearings hereinbefore referred to.

4. In an expansible gate, the combination of a central bar, parallel side bars one arranged on either side of the central bar, means for pivotally uniting the central bar and the side bars centrally of their length, caps carried by the ends of the central bar, trunnions on the caps, caps carried by the ends of the parallel side bars, bearings carried by the caps of the side bars to engage the trunnions of the caps of the central bar, said side bars being suitably perforated to permit engagement of the bearings and the trunnions hereinbefore referred to.

In testimony whereof, I affix my signature in the presence of two witnesses.

ALBERT SPIES.
